UNITED STATES PATENT OFFICE.

DOUGLAS S. DUFUR, OF THE DALLES, OREGON.

FEEDING DEVICE FOR TYPE-WRITERS.

SPECIFICATION forming part of Letters Patent No. 754,435, dated March 15, 1904.

Application filed June 25, 1903. Serial No. 163,055. (No model.)

To all whom it may concern:

Be it known that I, DOUGLAS S. DUFUR, a citizen of the United States, residing at The Dalles, in the county of Wasco and State of Oregon, have invented certain new and useful Improvements in Feeding Devices for Type-Writers; and I do hereby declare the following to be a full, clear, and exact description of the invention, such as will enable others skilled in the art to which it appertains to make and use the same.

The object of my invention is to provide a continuous-length paper feeding and taking-off mechanism.

15 A further object of my invention is to provide a line-number and sheet-length indicating and alarm device and a slide-scale for measuring any margin desired at the top or other part of each sheet.

20 While of more general application, my invention is here shown as particularly applicable to type-writing apparatus.

To these ends my invention consists in the construction, combination, and arrangement 25 of parts hereinafter described and claimed.

Referring to the drawings forming a part of this application and in which similar reference-letters indicate corresponding parts in the several views, Figure 1 is a perspective 30 view showing my invention applied to a type-writing machine. Fig. 2 is an elevation, on a larger scale, of the pneumatic means for actuating the type-writer carriage, the paper-reels, and the indicating device. Fig. 3 is an 35 axial sectional view of one of the take-off reels. Fig. 4 is an end elevation, partly broken away, showing the arrangement of the guide and tension rolls. Fig. 5 is a central vertical section showing the piston-valve and 40 its connections. Fig. 6 is a rear elevation, partly broken away, showing the mechanism for rotating the take-off reels. Figs. 7, 8, and 45 9 are detail views of the mechanism shown in Fig. 6. Fig. 10 is a rear view of the indicating and alarm device with the back cover-plate removed and the pneumatic actuating device shown in section. Fig. 11 is a front elevation of the indicator-dial. Fig. 12 shows 50 an adjustable device which can be set to activate the alarm at any desired point. Fig. 13

is a rear elevation of the indicating and alarm device. Fig. 14 is a detail view showing in side elevation the relative position of certain elements of the indicating and alarm device, and Fig. 15 is a side view of a slide-scale for 55 measuring the margin desired at the top of a sheet. Fig. 16 is a detail view of the carriage-actuating means.

Referring particularly to Fig. 1, A represents a base having suitable supports *a a*. B is a conventional representation of a type-writer, the keyboard and certain details being omitted for clearness. Upon the type-writer frame B' is supported the usual carriage B², carrying the platen B³. Pivoted to the under 60 side of the base A is a swinging arm C, provided at its lower end with a stirrup C'. A single-acting pneumatic cylinder D, conveniently attached to one of the supports *a*, is provided with the usual piston and piston-rod 65 D'. The forward cylinder-head may be provided with apertures D⁴ and any well-known form of valved piston employed. The outer end of piston-rod D' carries a cross-head D², arranged to travel on the guides D³, as clearly 70 shown in Fig. 1. The swinging arm C is operatively connected to the cross-head by the slot C⁵ in said swinging arm, which encompasses a pin on the cross-head. Through the rear head of cylinder D are tapped the pipes 75 E and F. The pipe F is open to the indicator I and to a pneumatic cylinder H, supported on the type-writer frame B', and the pipe E communicates with the piston-valve J, as shown especially in Figs. 1, 2, 5, and 10. A 80 pipe K establishes free communication between the piston-valve J and a cylinder L, carried by the base A for actuating the rotating mechanism of the take-off reels. As shown in Fig. 5, the piston-valve J embodies the cylinder J', piston J², piston-rod J³, an inlet E, and an outlet K. In the position shown the pipes E and K are in communication; but by moving the piston J² to a position intermediate the pipes E and K communication between 85 90 said pipes will be interrupted.

Referring now especially to Figs. 1, 6, 7, 8, and 9, the cylinder L is provided with a piston L' and piston-rod L², carrying a rack L³. The rack L³ is guided in constant mesh with 100

a pinion M, which pinion, together with its retaining-plate M⁶, is rigidly secured to the barrel M'. The barrel and attached pinion are loosely mounted on a shaft M¹¹, which is held from turning in its bearings M¹² M¹³ by any suitable means, as a key M¹⁴. The barrel incloses a spiral spring M², one end of which is secured to the barrel at M⁴ and the other end connected to the shaft M¹¹ at M⁵. A ratchet-wheel M⁸ and bevel-gear M⁹ are rigidly secured together and loosely mounted on the shaft M¹¹. A pawl M⁷, pivotally secured to the retaining-plate M⁶, engages ratchet-wheel M⁸ upon the rotation of the barrel M' by the spring M², but slides over said ratchet-wheel on the reverse motion of said barrel during the winding up of the spring M². A bevel-pinion M¹⁰ is secured to a shaft M¹⁵ in mesh with the bevel-gear M⁹. The shaft M¹⁵ is rotatably supported in brackets M¹⁶ M¹⁷ and carries a suitable number of disks M¹⁸, rigidly secured thereto, as by pins M¹⁹. Knurled nuts M²⁰ are threaded on shaft M¹⁵ adjacent to the disks M¹⁸ for confining one end of springs M²¹ and adjusting the tension of said springs. The other ends of the springs M²¹ bear against bevel-pinnions M²², loosely mounted on the shaft M¹⁵. Interposed between the disks M¹⁸ and bevel-pinnions M²² are friction-disks M²³, preferably of leather, against which the bevel-pinnions are held with a pressure regulated by the tension of springs M²¹. Meshing with each bevel-pinion M²² is a bevel-pinion O, secured to a short shaft O', journaled in a bracket O⁵. A plurality of shafts O² are journaled in the bracket O⁵ and arranged parallel to the shafts O', with which they are operatively connected by intermeshing gears O³. Each of the shafts O' O² carries means O⁴, preferably a flat bar, for supporting and rotating the take-off reels O⁶. The bracket O⁵ is provided with guide-rails O⁷ and O⁸ for the traveling carriage O⁹. The traveling carriage comprises two end members O¹⁰, between the lower portions of which are carried the feed-reels O¹¹. A bracket O¹³ is secured to traveling carriage O⁹ adjacent to the feed-reels O¹¹. This bracket is provided with members O¹⁴, having slots O¹⁵ arranged to receive the end journals of a plurality of tension and guide rolls O¹². Springs O¹⁶ are shown embracing the end journals of the tension-rolls O¹² for maintaining the periphery of such rolls in yielding contact. The take-off reels O⁶ are preferably arranged in the upper portion of the traveling carriage O⁹ and are supported at their left-hand ends by spring-pressed pins O¹⁸, shaped to fit sockets O¹⁹ in said rolls. Each reel O⁶ is provided with an axial bore O²¹, into which fits one of the flat bars O⁴, the reel being arranged to slide longitudinally on said bar and to rotate therewith. The flat bars O⁴ pass through openings O¹⁷ in the right-hand member O¹⁰ of the traveling carriage, such openings being sufficiently large to per-

mit free movement of the bars therein. A rod H² connects the traveling carriage O⁹ with the piston-rod H' of pneumatic cylinder H. The piston-rod H' is also connected by a resilient link H³ to a shaft H⁴, which is journaled in a bearing H⁵, carried by a rod H⁶, mounted to slide in the supports H⁷. The end of said shaft is also journaled in a bearing H⁸, which is supported on a pivot H⁹, arranged on the carriage axially with relation to the type-writer platen. The shaft H⁴ is shown carrying a pawl H¹⁰, which is constructed to rotate the type-writer platen for line-spacing; but this construction constitutes no part of applicant's invention as claimed in this application and need not be further described.

Referring especially to Figs. 10, 11, 12, 13, and 14, the indicating and alarm device I is provided with a front dial P, having any desired number of divisions and a pointer P'. The pointer P' and the ratchet-wheels P³ P⁴ are rigidly secured to a central spindle P², and said spindle extends beyond the rear of ratchet-wheel P⁴ sufficiently to receive the boss P⁵ of the adjustable part P⁶, as clearly shown. The adjustable part is provided with a tappet P⁷ and carries a pawl P⁸, pivoted to it at P⁹, and adapted for engagement with ratchet-wheel P⁴. An extension of boss P⁵ is mounted to turn in the rear cover-plate P¹¹, and an auxiliary pointer P¹⁰ is secured to said boss adjacent the rear side of said cover-plate. A yoke S is carried by the piston-rod S' of a piston S² and is provided with a guide-lug S⁴. A spring-pressed pawl S³ is secured to yoke S in position to engage ratchet-wheel P³. A spring-pressed detent S⁵ is pivoted to the indicator-frame and also engages ratchet-wheel P³. An alarm-bell S⁶ is mounted above the indicator, and a hammer S⁷ is pivotally connected at S⁸ to the indicator-frame in operative position with said bell. The lower portion of said hammer constitutes a pendulous latch S⁹, which is arranged to be engaged by the tappet P⁷ or by a tappet P¹² on ratchet-wheel P³. The latch S⁹ is provided with a shoulder adapted to compress a spring S¹⁰ to augment the striking effect of the hammer. The downward movement of piston S² may be effected by gravity or by a spring S¹¹, secured to said piston and to a pin S¹². Such downward motion of the piston may be limited by a shoulder S¹⁴. A slide-scale T is secured to the type-writer carriage by a screw T' and is shaped to approximately follow the periphery of the type-writer platen. This scale is provided with divisions corresponding to line-spaces and carries an adjustable slide member T². When using the slide-scale, the slide T² is set at that numbered division corresponding to the number of line-spaces which it is desired to leave as a margin at the top of a sheet. When the indicating and alarm device indicates that the last line on a sheet has been written, the type-writer

platens is rotated to bring such last-written line up to said slide T⁸, thus securing the desired space between the last-written line and the first line of the following sheet.

5 The operation of my apparatus is as follows: Feed-reels O¹¹, containing rolls of paper and transfer-paper, are placed in the lower portion of traveling carriage O⁹ and arranged to secure a sheet of transfer-paper interposed 10 between adjacent sheets of paper. The several sheets are then led between the guide and tension rolls, the sheet from the bottom reel being led between the first and second tension-rolls from the bottom, the sheet from the second 15 reel from the bottom being led between the second and third tension-rolls, &c., as shown in Figs. 1 and 4. The tension-rolls prevent slack in the paper-supply and insure an even unwinding of the feed-reels O¹¹. The sheets are 20 then carried between the usual platen and pressure-roll of the type-writer, partly around the platen, and finally to the take-off reels O⁶, as shown in Fig. 1. The operator then slides the 25 platen, together with the attached traveling carriage O⁹, to proper position and writes the first line of type-writing in the usual manner. After a line of desired length has been type-written the operator actuates the swinging arm C with his foot to temporarily compress air in 30 the rear end of cylinder D. Through the pipe F pressure is communicated from cylinder D to the pistons H⁴ and S². This pressure forces the piston H⁴ to the right, carrying with it 35 the type-writer platen and the traveling carriage O⁹, thus bringing them into proper position for the operator to start on the next line of type-writing. This movement of piston H⁴ also turns the type-writer platen for 40 line-spacing by means of connecting mechanism H³; but as this mechanism is claimed in a copending application, Serial No. 145,607, and forms no part of the invention claimed herein it need not be further described. These steps are repeated until the end of the 45 sheet is reached, when the operator turns the type-writer platen by hand sufficiently to provide for the desired margin at the top of the following sheet. The margin is measured by the sliding scale T, as hereinbefore described. 50 Before beginning to write, the operator sets pointer P' to the division numbered "1" on the dial P, and each time air is compressed in the cylinder D to return the type-writer platen into position for beginning a new line the 55 pressure communicated through pipe F to piston S² will actuate said piston and its attached yoke S, thereby rotating the ratchet-wheel P³ sufficiently to move the pointer P' to the next higher division on dial P. When 60 the pointer P' reaches the highest division on dial P, the tappet P¹² will trip latch S⁹ and ring the alarm-bell S⁶. If it is desired to have the alarm-bell sounded after any particular number of lines have been type-written, the 65 pointer P¹⁰ is set to the correspondingly-num-

bered division on the back cover-plate P¹, which will bring the tappet P⁷ into position to trip the latch S⁹ at the desired point. The piston-valve is normally set to permit communication between the pipes E and K, as 70 shown in Fig. 5, thus causing the piston L' to be actuated each time air is compressed in cylinder D. Each time the piston L' is so actuated it forces forward the rack L³ and places spring M² under tension, and upon the relief 75 of pressure in cylinder D the spring M² unwinds, thereby returning the rack L³ and piston L' to their initial position, ready to be again actuated by compression of air in cylinder D. The spring in unwinding rotates 80 the shaft M¹⁵ through the intermediary of pawl M⁷, ratchet M⁸, and bevel-gears M⁹ M¹⁰, as hereinbefore described. Such rotation of shaft M¹⁵ tends to rotate the bevel-gears M²², held by springs M²¹ against friction-disks M²³ of said shaft, and thus to wind up the paper on the take-off reels supported on flat bars O⁴. Should, however, the resistance of any take-up reel become abnormal, the corresponding bevel-gear M²² will slip 85 against its friction-disk, and thus prevent any tearing or injury of the paper.

Having thus fully described my invention, what I claim as new, and desire to secure by Letters Patent, is—

95

1. An attachment for type-writing machines, comprising a frame, a traveling carriage, paper-roll supports on said carriage for the supply and take-off, pneumatic means connected and arranged to actuate said carriage, and pneumatic means carried by said frame and connected and arranged to actuate said paper-roll supports, substantially as described. 100

2. An attachment for type-writing machines, comprising a frame, a traveling carriage, paper-roll supports on said carriage for the supply and take-off, means connected to actuate the carriage, means carried by said frame and constructed to actuate the take-off supports, and a common operating means connected to operate each of said actuating means, substantially as described. 105

3. An attachment for type-writing machines, comprising a frame, a traveling carriage, paper-roll supports on said carriage for the supply and take-off, tension-rolls on said carriage, means connected to actuate the carriage, means carried by said frame and constructed to actuate the take-off supports, and a common operating means connected to operate each of said actuating means, substantially as described. 115

4. An attachment for type-writing machines, comprising a frame, a traveling carriage, paper-roll supports on said carriage for the supply and take-off, tension-rolls on said carriage, and pneumatic means carried by said frame and connected to actuate the take-off supports, substantially as described. 125

5. An attachment for type-writing ma-

130

chines, comprising a frame, paper-roll supports for the supply and take-off rotatably supported on said frame, but held from longitudinal movement, a carriage arranged to travel in said frame along said paper-roll supports, reels removably supported through a portion of their length on said supports and constructed to rotate therewith and to slide longitudinally thereon, and detachable supports on said carriage arranged to engage the unsupported ends of said reels, substantially as described.

6. An attachment for type-writing machines, comprising a frame, a traveling carriage, paper-roll supports on said carriage for the supply and take-off, a line-space-indicating device, means connected and arranged to actuate said carriage, independent means connected and arranged to actuate said indicating device, and a common operating means connected and constructed to operate each of said actuating means, substantially as described.

7. An attachment for type-writing machines comprising a frame, a carriage arranged to travel in said frame, paper-roll supports on said carriage for the supply and take-off, said take-off supports comprising flat bars journaled in said frame, but held from longitudinal movement, openings in one member of said carriage through which the bars extend, reels provided with axial bores of approximately the same cross-section as that of said flat bars, whereby said reels may be removably supported on said bars to rotate therewith and slide longitudinally thereon, detachable supports on said carriage arranged to engage said reels, and means for rotating said flat bars, substantially as described.

8. An attachment for type-writing machines comprising a frame, a carriage arranged to travel in said frame, paper-roll supports on said carriage for the supply and take-off, means for actuating said carriage, means for actuating said take-off supports, a line-space-indicating device, and a common means arranged to operate the actuating means of the carriage, the take-off supports, and the indicating device, substantially as described.

9. An attachment for type-writing machines, comprising a frame, a carriage arranged to travel in said frame, paper-roll supports on said carriage for the supply and take-off, pneumatic means arranged to actuate said carriage, pneumatic means arranged to operate said take-off supports, a line-space-indicating device, pneumatic means arranged to operate said indicating device, a pneumatic compressor, and connections from said compressor to the pneumatic actuating means of the carriage, the take-off supports, and the indicating device, whereby said several actuating means are operated in common from said compressor, substantially as described.

10. An attachment for type-writing ma-

chines comprising a frame, a traveling carriage, paper-roll supports for the supply and take-off, a line-space-indicating device, and pneumatic means for actuating said carriage and indicating device, substantially as described.

11. An attachment for type-writing machines comprising a frame, a traveling carriage, paper-roll supports on said carriage for the supply and take-off, a line-space-indicating device, a slide-scale arranged for measuring the number of line-spaces to be left blank on any portion of the paper, and means for actuating said carriage and indicating device, substantially as described.

12. An attachment for type-writing machines comprising a frame, a traveling carriage, paper-roll supports on said carriage for the supply and take-off, a line-space-indicating device, a slide-scale arranged for measuring the number of line-spaces to be left blank on any portion of the paper, means for actuating said carriage, and independent means for actuating said indicating device, said actuating means being arranged and connected for simultaneous operation, substantially as described.

13. An attachment for type-writing machines comprising a frame, a carriage arranged to travel in said frame, paper-roll supports on said carriage for the supply and take-off, and pneumatic means carried by said frame for actuating the take-off supports, substantially as described.

14. An attachment for type-writing machines, comprising a frame, a carriage arranged to travel in said frame, paper-roll supports on said carriage for the supply and take-off, bevel-gears secured on the contiguous ends of said take-off supports, a shaft journaled in the frame, a plurality of friction-disks carried by said shaft, a series of bevel-gears loosely mounted on said shaft adjacent the friction-disks and arranged in mesh with the bevel-gears on the take-off supports, springs for yieldingly holding said second bevel-gears against the friction-disks, adjustable members arranged to regulate the tension of said springs, and means for rotating said shaft, substantially as described.

15. An attachment for type-writing machines, comprising a frame, a carriage arranged to travel in said frame, paper-roll supports on said carriage for the supply and take-off, bevel-gears secured on the contiguous ends of said take-off supports, a shaft journaled in the frame, a plurality of friction-disks carried by said shaft, a series of bevel-gears loosely mounted on said shaft adjacent the friction-disks and arranged in mesh with the bevel-gears on the take-off supports, springs for yieldingly holding said second bevel-gears against the friction-disks, adjustable members arranged to regulate the tension of said

springs, and pneumatically-actuated means for rotating said shaft, substantially as described.

16. An attachment for type-writing machines, comprising a frame, a carriage arranged to travel in said frame, paper-roll supports on said carriage for the supply and take-off, bevel-gears secured on the contiguous ends of said take-off supports, a shaft journaled in the frame, a plurality of friction-disks carried by said shaft, a series of bevel-gears loosely mounted on said shaft adjacent the friction-disks and arranged in mesh with the bevel-gears on the take-off supports, springs for yieldingly holding said second bevel-gears against the friction-disks, adjustable members arranged to regulate the tension of said springs, a pinion on said shaft, a gear arranged in mesh with said pinion, a ratchet-wheel carried by said gear, a stationary shaft on which said gear is loosely mounted, a barrel mounted to turn on the stationary shaft, a spring arranged with one end secured to said barrel and the other end secured to the stationary shaft, a gear carried by said barrel and provided with a pawl engaging with said ratchet-wheel, a rack arranged in mesh with said last-mentioned gear, and means for actuating said rack, substantially as described.

30 17. An attachment for type-writing machines, comprising a frame, a carriage arranged to travel in said frame, paper-roll supports on said carriage for the supply and take-off, bevel-gears secured on the contiguous ends of said take-off supports, a shaft journaled in the frame, a plurality of friction-disks carried by said shaft, a series of bevel-gears loosely mounted on said shaft adjacent the friction-disks and arranged in mesh with the bevel-gears on the take-off supports, springs for yieldingly holding said second bevel-gears against the friction-disks, adjustable members arranged to regulate the tension of said springs, a pinion on said shaft, a gear arranged in mesh with said pinion, a ratchet-wheel carried by said gear, a stationary shaft on which said gear is loosely mounted, a barrel mounted to turn on the stationary shaft, a spring arranged with one end secured to said barrel and the other end secured to the stationary shaft, a gear carried by said barrel and provided with a pawl engaging with said ratchet-wheel, a pneumatic cylinder having a piston and piston-rod, and a rack carried by said piston-rod and guided in mesh with said barrel-gear, whereby, upon the admission of pressure in the pneumatic cylinder, the rack will operate to place the barrel-spring under tension, and, upon the release of pressure in the pneumatic cylinder, said spring will act to rotate said pinion-carrying shaft and to return the rack to its initial position, substantially as described.

18. An attachment for type-writing machines, comprising a frame, a carriage arranged

to travel in said frame, paper-roll supports on said carriage for the supply and take-off, bevel-gears on the contiguous ends of certain of said take-off supports, spur-gears secured to the take-off supports which are so provided with 70 bevel-gears, spur-gears on certain other of the take-off supports and arranged in mesh with said first-mentioned spur-gear, bevel-gears arranged in mesh with the bevel-gears on the take-off supports, and means for rotating said 75 second bevel-gears, substantially as described.

19. An attachment for type-writing machines, comprising a frame, a carriage arranged to travel in said frame, paper-roll supports on said carriage for the supply and take-off, bevel-gears on the contiguous ends of certain of said take-off supports, spur-gears secured to the take-off supports which are so provided with 80 bevel-gears, spur-gears on certain other of the take-off supports and arranged in mesh with 85 said first-mentioned spur-gear, a shaft journaled in the frame, a plurality of friction-disks carried by said shaft, a series of bevel-gears loosely mounted on said shaft adjacent the friction-disks and arranged in mesh with the bevel-gears on the take-off supports, springs for yieldingly holding said second bevel-gears against the friction-disks, adjustable members arranged to regulate the tension of said 90 springs, and means for rotating said shaft, substantially as described.

20. An attachment for type-writing machines, comprising a paper-supply and take-off, a line-space-indicating and alarm device comprising a visual signal and an alarm device, mechanism arranged to actuate said visual signal, means carried by said mechanism and arranged to operate the alarm at a predetermined position of said signal, means for actuating the paper-supply and take-off, said actuating means being arranged and connected for simultaneous operation, substantially as described.

21. An attachment for type-writing machines, comprising a paper-supply and take-off, a line-space-indicating and alarm device comprising a dial and pointer, a spindle supporting said pointer, two ratchet-wheels secured on said spindle, a rear cover-plate constituting an auxiliary dial, a short shaft rotatably mounted in said cover-plate, an auxiliary pointer secured on the rear end of said shaft, an annular boss formed on the front end of said shaft and arranged to turn on the rear end of said spindle, a plate secured to said shaft adjacent the boss, a pawl carried by said plate and engaging with the rearward of said ratchet-wheel, a tappet carried by said plate, a tappet carried by the forward ratchet-wheel, an alarm-bell and hammer, a latch carried by said hammer and extending in the paths of the two tappets, a reciprocating member, a pawl carried by said member and engaging said forward ratchet-wheel, means for actuating said reciprocating member, and means for 130

actuating the paper-supply and take-off, said actuating means being arranged and connected for simultaneous operation, substantially as described.

- 5 22. An attachment for type-writing machines, comprising a frame, a carriage arranged to travel in said frame, paper-roll supports on said carriage for the supply and take-off, a line-space indicating and alarm device comprising
10 a dial and pointer, a spindle supporting said pointer, two ratchet-wheels secured on said spindle, a rear cover-plate constituting an auxiliary dial, a short shaft rotatably mounted in said cover-plate, an auxiliary pointer secured
15 on the rear end of said shaft, an annular boss formed on the front end of said shaft and arranged to turn on the rear end of said spindle, a plate secured to said shaft adjacent the boss, a pawl carried by said plate and engaging with

the rearward of said ratchet-wheels, a tappet 20 carried by said plate, a tappet carried by the forward ratchet-wheel, an alarm-bell and hammer, a latch carried by said hammer and extending in the paths of the two tappets, a reciprocatory member, a pawl carried by said member and engaging said forward ratchet-wheel, means for actuating said reciprocatory member, and means for actuating said carriage, said actuating means being arranged and connected for simultaneous operation, substantially as 25 described.

In testimony whereof I affix my signature in the presence of two subscribing witnesses.
